UNITED STATES PATENT OFFICE.

BENGT M. W. HANSON, DECEASED, OF HARTFORD, CONNECTICUT; EINAR A. HANSON AND CLARENCE E. WHITNEY EXECUTORS OF SAID BENGT M. W. HANSON, DECEASED.

TRUING DEVICE FOR GRINDING WHEELS.

Original application filed October 10, 1922, Serial No. 593,487. Divided and this application filed August 1, 1924. Serial No. 729,504.

This application is a divisional of my co-pending application Serial No. 593,487, filed October 10, 1922, for metal working machine.

of the grinding wheel and to be moved back and forth in each indexed position, as hereinafter described more in detail.

In the present illustrative disclosure, the grinding wheel slide *b* is mounted for adjustable movement on ways 10 which are generally at right angles to the axis of the work. The slide *b*, together with the grinding wheel carried thereby, may be moved up to, and away from, the work in any suitable manner, as by rotating the screw 11. The bearing box *c*, in which is journaled the grinding wheel spindle 12, is angularly adjustable on the slide *b* to permit the grinding wheel to be brought into

inclined position corresponding to the lead of the thread to be ground. As here shown, this box is mounted in a way 13, the center of curvature of which is the center of the wheel *d*, by which is meant a point at the axis of the wheel which is included in the plane bisecting the cutting edge of the wheel so that the axis about which the wheel may be angularly adjusted is on the line *a*—*b* (see Figs. 1 and 3) substantially perpendicular to the axis of rotation of the work. The grinding wheel spindle 12 may be driven in any suitable manner, as by means of a belt, not shown, passing about a pulley 14.

The slide or bearing member *h* is adapted to be fixed in any desired position of adjustment to the bracket *i* by bolts 20, the heads of which engage in T-slots 21 which are parallel to the ways 10 on which the grinding wheel slide is adjustable. Journaled in the bearing member *h* and adapted to be secured in any angular position of adjustment, as by means of a clamping bolt 22, is a pin or stud 23 to the forward end of which is fixed the post or support *g* having a vertically disposed bearing 24, the axis of which intersects the axis of the pin 23 at right angles. The axis of the pin 23 is coincident with the line *a*—*b*, that is to say, it is in a line passing substantially through the point about which the grinding wheel is angularly adjustable and perpendicular to the axis of the work. Mounted in the bearing 24 is a hollow shaft 25 having, at

10 the aim of the invention is to make certain improvements in a truing device of the type shown in my co-pending application Serial No. 391,013, filed June 23, 1920, for truing device.

15 In the accompanying drawing, wherein I have shown, for illustrative purposes, one embodiment which the invention may take:

Figure 1 is an assembly view of my improved truing device and grinding wheel, the truing device being shown in side elevation with parts in section;

Fig. 2 is an elevational view looking at the front or right hand end of Fig. 1;

Fig. 3 is a top plan view of the truing device;

Fig. 4 is a transverse section taken on line 4—4 of Fig. 1 and looking in the direction of the arrows.

Fig. 5 is a detail view; and

Fig. 6 is a view of a special thread.

Referring to the drawings in detail, *a* denotes a fixed bed or pedestal on which is mounted for movement towards and from the work a slide *b* carrying a journal box *c* in which is journaled a spindle or shaft for the grinding wheel *d*. The work or member to be threaded, and which is here designated by the letter *e*, is supported in any suitable manner as, for instance, by head and tail stock centers *f*, and these centers may be slidably carried by a rocking bed in the manner described in my said co-pending application Serial No. 593,487. The truing device is supported in a post or support *g* carried for angular adjustment in a slide *h* which is adjustably mounted on a bracket *i* secured to the bed *a*. The truing device has a re-sharpening tool, such as a diamond point *k*, which is adapted to be indexed to operate on the respective faces

its lower end, a projection 26 which carries a bolt or bearing member 27, the axis of which is substantially at right angles to the axis of the shaft 25 and parallel to the axis 5 of the pin 23 when the truing device is in mid position, that is, in a position to operate upon the flat or peripheral edge of the grinding wheel. Journalled on this bearing member 27 is an arm 28 in which is mounted 10 for longitudinal adjustment a sharpening or truing tool *k*, here shown as a diamond point. When the shaft 25 and the arm 28 are in the mid position shown in the drawings, the diamond point lies substantially 15 in the line *a*—*b*. The arm or tool carrying part 28 is provided with a segmental gear 32 with which meshes a bevel gear 33 carried by a shaft 34 journalled in the shaft 25 and carrying an operating 20 handle 35 at its upper end. It will be seen that, by swinging the handle 35 in opposite directions, the tool carrying part 28 will be oscillated through the gears 32 and 33 so as to move the diamond point *k* across the face 25 or edge of the grinding wheel being resurfaced. The shaft 25 and the parts mounted thereon, and which, as a whole, may be considered as the carriage, may be turned in the bearing 24 in order to bring the diamond point 30 into operative relation with any face of the grinding wheel, and, for the purpose of indexing it to the proper position, there is keyed to the upper end of the shaft 25 a plate 36 carrying, in a suitable 35 T-slot 37, adjustable dogs 38 adapted to abut against a stop 39 on the post *g*. For the purpose of holding the truing device in mid-position, the plate is provided 40 with a recess 41 in which a spring pressed plunger 42 is adapted to engage. The plate carries, on its edge, a scale 43 which cooperates with a zero mark 44 on the stop 39 so that the dogs may be properly adjusted. The shaft 25 may be locked in any position 45 of adjustment by turning the set screw 45. The numeral 48 designates a gauge arm carried by a pin 49 mounted in the bearing member 27. The lower end of this gauge arm carries a screw 50, the adjustment of 50 which in the gauge arm is determined by a plurality of interchangeable gauge members in the form of flat washers or discs one of which gauge members 51 is shown interposed 55 between the head of the screw 50 and the gauge arm. In Fig. 1, the gauge arm is shown in gauging position; during the grinding operation it is raised into inoperative position. By means of this gauge, the extent of the flat or truncated portion 60 of the grinding wheel is very accurately determined and produced. It is understood that as many gauge washers 51 will be provided as there are pitches of threads to be cut.

65 To set up the truing device for resurfac-

ing the wheel, where, for instance, a U. S. standard thread is being cut (in which case the faces of the thread are at an angle of 60° and the thread is truncated) the post or support *g* will be clamped in upright or 70 vertical position and the proper gauge member 51 will be selected for position upon the gauge arm 48. The diamond point will then be brought into engagement with the end of the screw 50. The gauge will then 75 be thrown into inoperative position, and the dogs 38 will be so adjusted that when respectively brought into engagement with the stop 39 the diamond point is in position to resurface the side faces of the wheel at 80 the proper (60°) angle in relation to each other. The shaft 25 will now be indexed or turned to bring one of these dogs into engagement with the stop 39 and the shaft 25 is then locked in this position by turning 85 up the clamping screw 45. The handle 35 is oscillated to move the diamond point back and forth across the side face of the wheel with which it is in engagement. After this side face is thus resurfaced, the clamping 90 screw 41 is loosened and the shaft 45 is turned until the other dog 38 engages the stop 39 and then the shaft is clamped in this position. The handle 35 is then oscillated to move the diamond point back and forth across the other side face of the grinding 95 wheel. After both side faces of the grinding wheel have been retrued, the shaft 25 is turned to a position where the plunger 42 engages in the recess 41 of the plate 36. 100 Then the diamond point is oscillated to effect the proper truncation on the periphery of the wheel.

When, for one reason or another, it is desired to retrue the edge of the grinding 105 wheel on a line other than that lying in a plane including the axis of the work, the post *g* may be inclined by turning the pin 23 on its axis to the desired angle and then clamping it in this position by the bolt 22. 110 This may be desirable where the pitch of the thread is extremely coarse or where a special thread is to be ground, the angle of the sides of which is measured on the normal pitch instead of the linear pitch of the 115 threaded member; also, where a special thread of such a shape as shown in Fig. 6 is to be ground the angle of inclination of the support or post *g* may be determined by the scale 43. This is a new feature which 120 is of considerable value from a commercial standpoint. When the thread such as shown in Fig. 6 is to be ground the side faces 55 may be resurfaced with the post *g* in upright position and then the surfaces 56 retrued with the post *g* in inclined position. It is to be noted that the axis of the pin 23 lies in the line *a*—*b*, and the diamond point 125 is indexable about the point of intersection of that line and the axis of the shaft 25. 130

It will be seen that the holder 57 for the diamond point is disposed at a slight angle in the arm 28. This arrangement is provided so that, when one portion of the diamond point is worn, by merely turning the holder on its axis a new sharp edge of this diamond point is in position to operate upon the wheel.

The truing device is in fixed relation to the work gauge after the latter has been adjusted to a piece of work and fixed in position, it being remembered that by this adjustment the work gauge is brought into fixed relation with the wheel. Consequently, these three parts, the work gauge, the wheel and the truing device, being once set for a piece of work of a given character, always remain so set with relation to one another for other work of like character.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A truing device including an angularly indexible carriage, means for indexing it, a tool on said carriage, and means for reciprocating said tool, said carriage being angularly adjustable about a line substantially at right angles to the axis about which it is indexed.

2. A truing device of the character described, including an angularly adjustable support, a carriage angularly indexible in said support about an axis substantially perpendicular to the axis about which said support is angularly adjustable, a resurfacing tool on said carriage, and means for reciprocating said tool substantially in a plane including the axis about which said support is adjustable and to which plane the axis about which said carriage is indexible is perpendicular.

3. A truing device of the character described, including an angularly adjustable support, a carriage angularly indexible in said support about an axis substantially perpendicular to the axis about which said support is adjustable, a resurfacing tool mounted for longitudinal adjustment substantially on the line of the axis of said support, and means for reciprocating said tool.

4. A truing device of the character de-

scribed, including an angularly adjustable support, a hollow shaft journalled therein at right angles to the axis of said support, means for indexing angularly said shaft about its own axis, a bearing member carried by said shaft and parallel to the axis about which said support is adjustable, an arm journalled on said bearing member, a resurfacing tool longitudinally adjustable in said arm, a segmental gear on said arm, and a shaft journalled in said hollow shaft and having a gear meshing with said segmental gear.

5. In combination, a grinding wheel; and a truing device including a support angularly adjustable relative to said wheel and about a diametrical line passing through said grinding wheel, an angularly indexible carriage on said support, and a resurfacing tool mounted for reciprocating on said carriage.

6. In combination, a grinding wheel; and a truing device including a support angularly adjustable relative to said wheel and about a diametrical line passing through said grinding wheel, a carriage angularly indexible in said support about an axis substantially perpendicular to the axis about which said support is angularly adjustable, a single resurfacing tool on said carriage, and means for reciprocating said tool substantially in a plane including the axis about which said support is angularly adjustable and to which plane the axis about which said carriage angularly adjustable is perpendicular, said grinding wheel being movable to and from said tool on said diametrical line.

7. In combination, a grinding wheel; and a truing device including a support angularly adjustable relative to said wheel and about a diametrical line passing through the center of the wheel, a carriage angularly indexible in said support about an axis substantially perpendicular to said line, and a resurfacing tool on said carriage and movable in a plane including the said line and substantially perpendicular to the axis about which said carriage is indexible.

8. In combination, a grinding wheel angularly adjustable about a diametrical line passing through its center; and a truing device angularly adjustable relative to said wheel and about that line and having a reciprocable resurfacing tool angularly indexible about an axis perpendicular to that line.

9. In combination, a grinding wheel movable on and angularly adjustable about a diametrical line passing through its center and included in a plane bisecting the angle of the cutting edge of said grinding wheel; and a truing device angularly adjustable about that line and having a resurfacing tool indexible about an axis perpendicular to, and about a center lying in, said line.

10. In combination, a work holder on which the work is rotated; a grinding wheel angularly adjustable about a diametrical line passing through its center and intersecting the axis of the work, said line being included in a plane bisecting the angle of the cutting edge of the grinding wheel; and a truing device including a support angularly adjustable about that line as an axis, a carriage in said support indexable about an axis intersecting that line, and a resurfacing tool on said carriage adapted to be moved in a plane including that line.

BENGT M. W. HANSON.
